UNITED STATES PATENT OFFICE.

WILLIAM A. McGINNIS, OF DETROIT, MICHIGAN.

GARMENT-HANGER.

1,345,017.

Specification of Letters Patent. Patented June 29, 1920.

Application filed September 15, 1919. Serial No. 323,874.

To all whom it may concern:

Be it known that I, WILLIAM A. McGINNIS, a citizen of the United States of America, residing at Detroit, in the county 5 of Wayne and State of Michigan, have invented certain new and useful Improvements in Garment-Hangers, of which the following is a specification, reference being had therein to the accompanying drawings.

10 In my patent #1,273,253, granted July 23, 1918, there is disclosed a garment hanger consisting of two foldable hanger arms and two foldable or collapsible spreader arms adapted to be housed by the hanger arms 15 when said arms are folded or swung into parallelism with each other. This particular form of garment hanger includes certain pieces of hardware and I have found that some of the pieces of hardware can be 20 improved to simplify the construction and assembling of the hanger parts, and generally improve the hanger.

My improvements will be hereinafter considered and then claimed, and reference will 25 now be had to the drawing, wherein—

Figure 1 is a front elevation of the garment hanger in an open or extended position;

Fig. 2 is a similar view of the same, closed, 30 and partly broken away and partly in section;

Fig. 3 is an enlarged detailed sectional view taken on the line III—III of Fig. 1, and

Fig. 4 is a longitudinal sectional view of 35 a detached socket member.

As in my former patent there are two hanger arms 1 and 2 having the inner ends thereof pivotally connected so that the arms 40 may be folded or swung into parallelism, and to maintain the arms extended and in a useful position there are two spreader arms 3 and 4 from which may be suspended trousers or other garments.

45 The hanger arms 1 and 2 have the confronting faces thereof longitudinally grooved, as at 5 and 6 respectively, and in the outer ends of these grooves are the outer ends of the spreader arms 3 and 4, said 50 spreader arms being made of channel material with the inner ends thereof pivotally connected together, as at 7, so that the arm 3 may be swung partly into the arm 4 and both of said spreader arms housed within the 55 confronting grooves 5 and 6 when the hanger

arms 1 and 2 are closed. The spreader arms 3 and 4 may be provided with suitable clips 8 for retaining a garment in engagement therewith.

The hanger arm 1 is of less length than 60 the hanger arm 2 so that the inner end or head 9 of the arm 2 will overlie the end of the arm 1 and the arm 1 has its groove 5 open at the inner end of said arm. Communicating with the open end of the groove 65 5 is a groove 10 which merges into the end face of said arm, as best shown in Fig. 2, and this groove is adapted to receive a central channel portion 11 of a metallic socket member 12 mounted on the end of the arm 70 1 and connected thereto by nails, rivets, prongs or similar fastening means, generally indicated at 13. The socket member 12 provides two channels 14 to receive the walls 15 of the grooves 5 and 10 and with 75 the outer walls 16 of the socket member extending onto the outer walls of the hanger arm 1, it is practically impossible for the inner end of the hanger arm 1 to split or become worn during the use of the garment 80 hanger. The shape of the socket member 12 is such as to provide contacting faces 17 for the end or head 9 of the hanger arm 2, and said socket member affords four walls, as 85 shown in Fig. 3, through which a pivot pin 18 may extend for holding the pivot plate 19 of the hanger arm 2. The pivot plate 19 is mounted in a kerf 20 provided therefor in the arm 2 at the inner end 90 of the groove 6, said pivot plate being held 90 by rivets 21 or other fastening means. The plate 19 is shaped, as shown in Fig. 2, to provide clearance for the pivoted ends of the spreader arms 3 and 4, and to extend into the channel portion 11 of the socket 95 member so that the pivot pin 18 may pass therethrough and articulate the hanger arms 1 and 2. The channel member 11 is of a width to engage the side walls of the pivot plate 19 and prevent lateral movement of 100 one arm relative to the other and this is further provided for, when the arms are closed, by a dowel pin 22 carried by the outer end of the arm 1 and adapted to extend into a recess 23 in the outer end of the 105 arm 2.

A conventional form of hook or suspension member 24 may be pivotally connected to the inner end or head 9 of the arm 2 and extend through the pivot plate 19, so as to 110

prevent the hook from injuring the wood or material from which the hanger arms are made.

Metallic caps may be mounted on the 5 outer ends of the arms 1 and 2 to prevent said arms from splitting or becoming otherwise injured.

I attach considerable importance to the 10 socket member 12, constituting one of the pieces of hardware, and would have it understood that the other pieces of hardware are susceptible to such changes as fall within the scope of the appended claims.

What I claim is:—

- 15 1. In a garment hanger, the combination with hanger arms having the outer ends thereof connected by spreader arms, of a socket member mounted on the end of one of said hanger arms and providing a central channel and side channels with the latter disposed to embrace side walls of said hanger arms, and a pivot plate mounted in the other hanger arms and extending into

the central channel of said socket member and pivotally connected thereto. 25

2. The combination with hanger arms adapted to have the ends thereof pivotally connected together so that said arms may be swung into parallelism, and a pivot plate carried by one of said arms, of a socket 30 member mounted on the other arm and providing three channels, one of which receives a pivot plate of the other hanger arm and the other two channels receive side walls of the socket carrying arm, and a pin extending through parallel walls of the three channels of said socket member to retain said pivot plate in engagement with said socket member. 35

In testimony whereof I affix my signature 40 in the presence of two witnesses.

WILLIAM A. McGINNIS.
